CORN CURE PACKAGE

Bertie Ellis, New York, N. Y.

Application April 3, 1934, Serial No. 718,751

3 Claims. (Cl. 206—47)

This invention relates to new and useful improvements in a corn cure package.

The invention has for an object the construction of a corn cure package which is characterized by the arrangement of a bottle for holding liquid for initial application to the corns, calluses, etc., mole skin adhesive pads secured around said bottle, and a wrapping of "cellophane" or similar material to expose the bottle and pads.

Still further, the invention contemplates the arrangement of a means comprising sheet material for removably holding the adhesive pads in place around the bottle.

Still further, the invention also contemplates arranging several protectors for corns within the package of "cellophane."

As another object of this invention numerous novel means are proposed for securing the adhesive pads around said bottle and in said package.

The corn cure package according to this invention has the feature that the liquid may be applied first for removing the corns, calluses, etc., and then the next day, or many hours later the moleskin adhesive pads may be applied to destroy the root by protecting the tissues or under-skin. This arrangement insures convenience and cleanliness.

Still further, the invention contemplates the construction of a package as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is an elevational view of a corn cure package according to this invention.

Fig. 2 is a developed view of one portion of the sheet used for holding the adhesive pads detachably about the bottle.

Fig. 3 is a plan view of another part for association with the part illustrated in Fig. 2.

Fig. 4 is a side elevational view of another corn cure package constructed according to a modification of this invention.

Fig. 5 illustrates a holder for the bottle when assembled in a package according to this invention.

Fig. 6 is a developed view of Fig. 5.

Fig. 7 is a perspective view of another form of holder.

Fig. 8 is a developed view of Fig. 7.

Fig. 9 is a perspective view of another form of holder.

Fig. 10 is a developed view of Fig. 9.

Fig. 11 is a perspective view of still another form of holder.

Fig. 12 is a developed view of Fig. 11.

Fig. 13 is a perspective view of still another form of holder.

Fig. 14 is a developed view of Fig. 13.

Fig. 15 is a perspective view of another form of holder.

Fig. 16 is a developed view of Fig. 15.

Fig. 17 is a developed view of another form of holder.

Fig. 18 is a perspective view of another corn cure package according to this invention.

Fig. 19 is another perspective view of another embodiment of this invention.

Fig. 20 is another perspective view illustrating a still further embodiment.

The corn cure package according to this invention, comprises a bottle 10 containing a liquid corn cure, callus, wart and the like remover arranged within a wrapper of "cellophane" 11.

A strip of gauze 12 partially encircles the bottle 10 and several moleskin adhesive pads 13 are attached on the gauze 12.

A means is provided for securing the gauze pads in position around the bottle even though the wrapping 11 be removed.

This means comprises sheet material having a bottom portion 14 for location on the bottom of the bottle and several arms 15 constituting continuations from the sides of the bottom portion 14 and extending upwards along the sides of the bottle serving to hold the adhesive pads in place.

The upper ends of the arms 15 engage within an opening 16 formed in a sheet material member 17 which rests upon the shoulder immediately adjacent the neck of the bottle.

Friction is depended upon to maintain the ends of the arms 15 clamped within the opening 16.

The "cellophane" wrapping furthermore serves to bind these parts together as a unit.

A feature of this invention lies in the fact that the "cellophane" wrapper 11 may be removed to expose the bottle for use.

The stopper of the bottle can be removed and the liquid applied to the parts to be treated.

The adhesive pads 13 will maintain their positions and so avoid any possibility of accidental misplacement.

After results have been obtained with the liquid corn

cure the pads 13 may be removed and applied as is necessary for full treatment.

In Fig. 4 a modified form of the invention has been disclosed in which a package is illustrated which is substantially similar to the package illustrated in Fig. 1 except for the fact that a different means is provided for securing the adhesive pads detachably in place. This latter means comprises a band 18 of sheet material encircling the bottle and serving to hold the adhesive pads in place. The other parts of the package will be recognized by corresponding reference numerals to the form previously described. Another distinction resides in the fact that several pads 19 are also arranged within the "cellophane" wrapping 11 which pads are intended to be engaged on the corn or other part to prevent pressure of the shoe and consequent irritation.

Various means may be substituted for the means previously described for holding the adhesive pads in position about the bottle. In Figs. 5-17 inclusive details will be given only of various holding means, per se, since the manner in which the bottles of liquid corn cure and pads are associated with the holding means is obvious, these parts being combined in a package as described in Figs. 1-4.

The holding means illustrated in Figs. 5 and 6 comprise a strip of material which is bent so as to produce a central portion 20, and top and bottom portions 21 extending at right angles thereon. It is intended that the bottle with the gauze and adhesive pads 13 be engaged so as to rest upon the lower portion 21 and with the top of the stopper of the bottle engaging the underside of the top portion 21. Then the package is completed with the "cellophane" wrapper.

In Figs. 7 and 8, another arrangement of holding means has been disclosed which comprises a strip of material bent transversely so as to produce a holding element comprising four sides, but open at the front and rear. More particularly, this holding element consists of sides 22 connected with top and bottom ends 23. A small flap 24 merely serves to provide for securing the strip together as a unit. With this arrangement the bottle with the gauze and adhesive pads around the sides thereof, is engaged within the opening to rest upon the bottom and touch the top.

In Figs. 9 and 10 another variation of holding means has been disclosed which is identical substantially to the arrangement illustrated in Fig. 5 except for the fact that another portion 26 is provided for closing one of the sides. This portion 26 is also provided with a flap 27 by which it may be secured in position.

In Figs. 11 and 12 another variation of holding means has been disclosed which makes use of a form very similar to the arrangement illustrated in Fig. 7 except for the provision of front and rear fragmentary sides 28. This holding means is produced from one integral sheet as illustrated in Fig. 12. The flap 24' serves to hold the band together, and one of the portions 22 is provided with the side portions 28 which are merely bent into position.

In Figs. 13 and 14 another variation has been disclosed which is similar to the arrangement illustrated in Fig. 11 except for the fact that a continuation 30 connected the front and rear portions 28'. Still further, the sides 22' of this means are of slightly greater lengths than the similar sides previously mentioned. With this arrangement

it is intended that the liquid bottle with the gauze and adhesive pads holding it be engaged into the holder so that the top of the stopper of the bottle engages beneath the top 23 and the bottom of the bottle rests upon the edge 31 of the continuation 30. The portions 28' merely engage the sides of the bottle to hold the bottle in position. The areas of the holder not used are for the purpose of holding pads such as the pads 19 or other similar articles.

In Figs. 15 and 16 another holder has been disclosed which is substantially in the shape of a box having a cover 32 formed with an opening 33 closed by a cellophane or other transparent sheet of material 34. This box is formed with portions 35 and 36 dividing off a small area thereof. An edge flap 37 is arranged on one side of the box. The liquid bottle with the pads surrounding it may be engaged in the opening in the box and adhesive pads or other pads may be stored within the compartment and closed by the portions 35 and 36.

In Fig. 17 another holder has been disclosed which is very similar to the arrangement illustrated in Fig. 5 except that the holder comprises a side portion 40 formed with top and bottom portions 41 which are connected with fragmentary front and rear portions 42 and 43 provided with flaps 44 adapted to engage in slots 45 in the portion 40 to hold the holder in position.

In Fig. 18 another corn cure package has been illustrated which comprises a transparent non-breakable container 47 having a removable non-breakable transparent top 48. This container is shown of circular shape in transverse cross section. The corn cure package as previously illustrated may be placed within this container and the merchandise sold in this fashion. For example, as illustrated in Fig. 18 the corn cure package shown in Fig. 4 is within the container. The reference numerals of the corn cure package may be readily recognized for identifying the parts previously described.

In Fig. 19 a variation of the invention has been disclosed in which the corn cure package illustrated in Fig. 4 is shown within a container 47 which is of transparent non-breakable material. This container is not equipped with a cover as previously explained relative to Fig. 18. In other respects this form is identical to the previous arrangement.

In Fig. 20 another variation of the invention has been disclosed in which the transparent non-breakable container 47 holds a corn cure package comprising a sheet of cardboard 49 to which a bottle of corn cure 50 and a card 51 with corn pads 52, is secured by a "cellophane" wrapping 53. This "cellophane" wrapping engages over the bottle 50 and the pad 51 to hold these parts in a unit. The entire unit is then engaged within a container 47 and slightly projects from the top so as to be easily removable and completely viewable through the material of the container piece.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A corn cure package, comprising a bottle for liquid corn cure for initial application on corns, calluses, warts and the like, mole skin adhesive

pads located around the sides of said bottle for subsequent application to the areas treated to destroy the root of the corn, etc., by protecting the tissues or underskin, means for securing said pads detachably in position to arrange for the use of the liquid of the bottle without disturbing the pads, and a "cellophane" or other similar wrapping around the bottle and holding the parts as a unit, said means for securing the pads comprising a sheet strip bent and secured to form sides, top and bottom for receiving and holding the bottle, but open at the front and back and front and rear portions partially extending across the open front and rear sides.

15 2. A corn cure package, comprising a bottle for liquid corn cure for initial application on corns, calluses, warts and the like, mole skin adhesive pads located around the sides of said bottle for subsequent application to the areas treated to destroy the root of the corn, etc., by protecting the tissues or underskin, means for securing said pads detachably in position to arrange for the use of the liquid of the bottle without disturbing the pads, and a "cellophane" or other similar wrapping around the bottle and

holding the parts as a unit, said means for securing the pads comprising sheet material bent and secured to form opposite sides connected by a top and a bottom, and front and rear portions partially extending across the open front and rear sides. 5

3. A corn cure package, comprising a bottle for liquid corn cure for initial application on corns, calluses, warts and the like, mole skin adhesive pads located around the sides of said bottle for subsequent application to the areas treated to destroy the root of the corn, etc., by protecting the tissues or underskin, means for securing said pads detachably in position to arrange for the use of the liquid of the bottle without disturbing the pads, and a "cellophane" or other similar wrapping around the bottle and holding the parts as a unit, said means for securing the pads comprising sheet material bent and secured to form opposite sides connected by a top and a bottom, and front and rear portions partially extending across the open front and rear sides, and a continuation extending transversely across the free edges of said front and rear portions.

BERTIE ELLIS. 25
